Filed Jan. 24, 1968, Ser. No. 10,291

Term of patent 14 years

Int. Cl. D8—03

U.S. Cl. D15—8

FIG. 1 is a perspective view of a combined hat and coat hook embodying my novel design;

FIG. 2 is a side view of the coat hook shown in FIG. 1, the opposite side being identical;

FIG. 3 is a top view of the coat hook shown in FIGS. 1 and 2; and

FIG. 4 is a front elevational view of the coat hook shown in FIGS. 1 through 3.

The dotted lines of FIGURE 1 are for illustrative purposes only.

I claim:

The ornamental design for a combined hat and coat hook, as shown and described.
